UNITED STATES PATENT OFFICE.

CHRISTOPHER GRIMSHAW, OF MILWAUKEE, WISCONSIN.

IMPROVEMENT IN BREECH-LOADING ORDNANCE.

Specification forming part of Letters Patent No. 33,582, dated October 29, 1861.

To all whom it may concern:

Be it known that I, CHRISTOPHER GRIMSHAW, of Milwaukee, in the county of Milwaukee and State of Wisconsin, have invented a new and useful Improvement in Breech-Loading Cannon; and I do hereby declare that the following is a full, clear, and exact description of the same, reference being had to the accompanying drawings, making part of this specification, in which—

Figure 1 is a plan of a cannon with my improvement. Fig. 2 is a horizontal axial section of the same. Fig. 3 is an elevation of the rear end thereof.

Similar letters of reference indicate corresponding parts in the several figures.

My invention relates to the class of breech-loading cannon which has a bore extending completely through, and a movable plug inserted transversely of the latter; and the improvement consists in a novel construction of parts, adapting the plug to be continued tight and effective when the piece has become distorted by use.

To enable others skilled in the art to make and use my invention, I will proceed to describe its construction and operation.

A is the bore, extending completely through from end to end, and rifled, with the exception of a chamber at the breech, which receives the cartridge in loading. The body of the gun is enlarged at the breech, and provided on each side with a cylindrical projection, B, pierced with a conical aperture, extending completely through the gun transversely to its bore, and of larger diameter than the latter.

C represents a conical plug, ground to fit the transverse aperture, so as to form a gas-tight joint. When in position, the plug C is secured by a key, c.

To load the gun, the plug C is withdrawn and the cartridge inserted from the rear. The plug being then replaced, the piece is ready to fire. The enlargement and form of the breech compensate for the cutting away of metal to

admit the plug, and thus secure the requisite degree of strength.

The round plug possesses many important advantages over a square one. It is much stronger in proportion to its size, and requires a proportionately smaller aperture in the gun to receive it. As the gun expands by use, and the aperture becomes elongated and enlarged by this action and by the force exerted upon the plug by the explosion, the round plug may readily be kept tight by grinding, whereas to fit a square plug to its aperture requires a skilled mechanic.

For ships' guns the projections B afford convenient means of attachment for stay-ropes, as shown in Fig. 1, to resist the recoil of the gun.

For the heaviest ordnance a lever or other mechanical appliance may be employed to insert and withdraw the plug.

The gun, being bored completely through, is adapted for the use of telescopic lenses for sighting through the barrel. Such lenses are shown in Fig. 2 in positions occupied when the piece is discharged.

I am aware that a perforated faucet breech-plug has been used for admitting the charge through it. This, therefore, I do not claim; but,

Having thus described my invention, what I claim as new, and desire to secure by Letters Patent, is—

A breech-loading cannon bored completely through from end to end, and provided with a circular tapering solid breech-plug ground to fit a corresponding aperture extending transversely through the bore, and of larger diameter than the latter, all as hereinbefore explained.

The above specification of my improvement in breech-loading cannon signed this 21st day of September, 1861.

CHRISTOPHER GRIMSHAW.
